ATTORNEY

UNITED STATES PATENT OFFICE.

HARRY SEIGMAN, OF NEW YORK, N. Y.

REST FOR SADIRON.

Application filed April 27, 1925. Serial No. 25,997.

My invention relates to rests for sad irons of the type adapted for household use and for use by tailors, garment workers and other operators who constantly use sad irons 5 in their work.

More particularly stated my invention relates to a rest, to be detachably fitted upon a stand for the type commonly used for supporting the sad iron. The stand with this 10 rest mounted upon it having advantages over the stand when used without the rest.

Reference is made to the accompanying drawing forming a part of this specification and in which like reference characters indicate like parts throughout the several 15 figures.

Figure 1 is a substantially central longitudinal section through a stand carrying my improved rest and an iron supported 20 thereupon.

Figure 2 is a fragmentary plan of the same certain parts being broken away.

Figure 3 is a section on the line 3—3 of Figure 2 looking in the direction indicated 25 by the arrows.

Figure 4 is an inverted plan or bottom view of my improved rest, shown without other parts.

A stand 5 of the kind commonly used for 30 supporting sad irons, is provided with legs 6, 7 and feet 8, 9. The stand 5 is further provided with a marginal rib 10 and with a number of other ribs 11, the ribs 11 being parallel with each other and having their 35 top edges a little lower than the adjacent top edge of the marginal rib 10, as may be understood from Figure 3.

A board 12, made preferably of asbestos or some other fire-proof material, is provided 40 with channels 13, parallel with each other and spaced apart and substantially in registry with the ribs 11, as indicated in Figure 3. The asbestos board 12 is further provided adjacent its edges with a marginal shoulder 14 so formed and arranged as to be substantially in registry with the marginal rib 10 of the stand when the board 12 is rested upon the stand, as may be understood from Figure 3.

50 A piece of netting 15 is carried by the board 12, and is provided with corrugations 16 which are always in registry with the channels 13 and which are brought into registry with the ribs 11 whenever the board 55 rests upon the stand. The piece of netting 13 is further provided with portions 17, bent

into conformity with the shoulders 14, and is further provided with portions 18 which are bent up over the top of the board, and serve to hold the netting in position upon the board. The netting is to protect the asbestos board, and to prevent it from becoming shredded or chipped; and also to prevent the undue localization of heat upon the board and parts contiguous thereto. 60 65

My purpose in providing the ribs 11, corrugations 16 and channels 13 is to prevent the asbestos board from being driven sideways, under the intermittent and somewhat haphazard pounding action of the iron, and 70 particularly if the marginal shoulder of the board becomes misshapen from wear.

The asbestos board 12 carries a pair of hooks 19, each integral with a shaft 20, which extends through a hole in the board. 75 The shaft 20 is integral with the hooks 19, and so arranged that these hooks can be swung or turned relatively to the board. Another hook 21, carried by a shaft 22 and integral therewith, is mounted upon the board 12, the hook 21 and shaft 22 being made of wire. The shaft 22 extends through one of the grooves 13, and is tucked under the middle portion of the shaft 20 according to Figure 4, so as to rest upon the shaft 20 when the apparatus is in the position indicated in Figure 1. The hook 21 as thus mounted is free to turn or swing relatively to the board, and this mounting for the hook is found in practice to be satisfactory for the 80 purpose here contemplated. 85

A number of spiral compression springs 23 are carried by the netting 15, and thus 90 constitute supports for the board 12. The board 12, carrying the netting 15, hooks 19 and 21 and spring supports 23, collectively 95 constitute a complete article shown in Figure 4, and this article as a whole I designate as a rest for supporting a sad iron. In order to mount my improved rest upon the stand 100 105 110 115 120 125 130 135 140 145 150 155 160 165 170 175 180 185 190 195 200 205 210 215 220 225 230 235 240 245 250 255 260 265 270 275 280 2 By pressing the board 12 downward, however, the spring supports 23 are compressed slightly so that the corrugations 16 of the netting are lowered into engagement with the upper edges of the ribs 11. This cushions the board 12, because the corrugations 16 of the netting have like the spring supports 23 a little resiliency.

10 A sad iron is shown at 24 and is provided in the usual manner with handle members 25 which in Figure 1 are shown as broken away.

15 Whenever the said iron is placed upon my improved rest as indicated in Figure 1 the weight of the iron depresses the board slightly, so that the iron is supported with a slight cushioning. Because of this fact, the sensation experienced by the operator by placing the iron upon the rest and removing it therefrom is rather pleasant, owing to the absence of any shock or jar due to the movement of the iron.

20 The board 12 of fireproof material can easily be kept clean so that when the said iron is repeatedly rested upon and removed from it, the iron does not pick up dirt from the board.

25 A great advantage of my improved rest is that when the sad iron is quickly placed upon it there is no ringing sound. Ordinarily when a sad iron is placed upon the stand there is a harsh metallic ring, due to the impact of the iron upon the stand. This might seem to be a trivial matter, but workers who hear this ringing sound from morning till night and day after day for months and years become very tired of it, and it gradually becomes more and more disagreeable to them. Moreover, in a large establishment where several dozen workers are employed, the constant ringing sound is not only disagreeable to the workers, but injuriously affects their hearing. This is prevented by my improved rest.

50 My improved rest conserves the heat of the said iron because the board 12 of asbestos or other suitable fireproof material does not allow the heat of the iron to be conducted away and unduly wasted. Thus my device promotes economy, in avoiding undue waste of heat.

55 My device is well adapted for use as an article of manufacture, and may be cheaply made up in quantity production, and of parts easily standardized.

60 I do not limit myself to the precise mechanism shown, as variations may be made therein without departing from my invention, the scope of which is commensurate with my claims.

I claim:

65 1. A device of the character described comprising a stand provided with ribs spaced apart, a board of fireproof material provided with channels spaced to register with said ribs, a netting mounted upon said board and provided with corrugations extending into said channels for registering with said ribs, and means for supporting said board adjacent said stand and in spaced relation thereto.

70 2. A device of the character described comprising a stand provided with ribs spaced apart and further provided with a marginal rib, a board of fireproof material provided with channels spaced apart and substantially in registry with said first mentioned ribs, said board being also provided with a marginal shoulder to register with said marginal rib, a piece of netting carried by the lower face of said board, and spring supports located between said board and said stand for normally supporting said board out of engagement with said stand.

75 Signed at New York city, in the county of New York and State of New York, this 25th day of April, 1925.

HARRY SEIGMAN.
